UNITED STATES PATENT OFFICE.

NATHAN C. HEATON, OF WESTMONT, ILLINOIS, ASSIGNOR TO MONTGOMERY WARD & CO., INC., OF CHICAGO, ILLINOIS, A CORPORATION OF ILLINOIS.

STENCIL-CUTTING ATTACHMENT FOR TYPEWRITERS.

Application filed October 20, 1923. Serial No. 669,650.

The present invention has to do with type-writing machines of the flat-platen type, and contemplates an attachment therefor which may be utilized for printing, as well as stencil cutting.

Book or flat-platen typewriting machines frequently are utilized for printing and stencil cutting in the making of records. As commonly constructed, the positioning of the writing head in the operations mentioned is rendered difficult and uncertain because of the lack of proper mechanism for accurately guiding and locating the head over the platen and the material to be printed or cut. Loss of time results, and the surface printed or cut lacks uniformity in its location of the matter recorded thereon.

Among the objects sought to be attained by the present invention is the provision of novel and effective means which enables the operator to position the writing head at the proper points on the writing surface area, or areas to be stenciled, without the necessity of inspecting that area, or to search laboriously for the proper point thereon at which to position the writing head for the desired operations.

A further object of the invention is the provision of novel means for maintaining the material to be printed or cut in proper relation to the platen, thereby to retain the same substantially flat on the platen, and enable the keys of the writing head to be operated in the making of the record with a minimum degree of effect, as well as with a maximum degree of accuracy in the movement of the type towards and into contact with the material to be acted on.

Incidental to the foregoing, the invention also contemplates mechanism of the character referred to whereby the writing head, as when a stencil sheet is to be cut, may be placed in definite and predetermined position over the platen so that fall of the type on to the stencil sheet will be insured in the area covered by the normal ink spot made on the stencil sheet when the latter is placed in an imprinting machine or device. Accuracy of position of the stenciled matter with respect to such ink spot thus is attained, and the operator is not required to exercise any special care or skill in positioning the head for the cutting operation.

Other objects and advantages will become apparent as the nature of the improvements

is better understood, the invention consisting substantially in the novel construction, combination and arrangement of parts hereinafter described, illustrated in the accompanying drawings, and finally pointed out in the appended claims.

The form of the invention herein set forth is intended to delineate a practical adaptation of the inventive concept, but the invention is not limited to such embodiment, and the disclosure thus made is to be taken in an illustrative and not a restrictive sense.

In the drawings—

Fig. 1 is a top plan view of the herein described attachment in its application to a flat-platen typewriting machine, the dotted lines illustrating one position of the writing head occupied by the latter with respect to the attachment.

Fig. 2 is an end elevation of the construction illustrated in Fig. 1, a portion being in section, and the writing head being omitted.

Fig. 3 is a detail sectional view on the line 3—3, Fig. 1.

Fig. 4 is a similar view, on the line 4—4, Fig. 1.

Fig. 5 is a face elevation of a record card and stencil sheet with respect to which the herein described invention has particular utility.

Fig. 6 is a side elevation illustrating the attachment in its application to a flat-platen typewriting machine, the head thereon being positioned as when adapted for printing purposes.

Fig. 7 is a similar view, the head of the typewriting machine being positioned as when adapted for stencil cutting purposes.

Fig. 8 is a detail sectional view on the line 8—8, Fig. 7.

Referring now in detail to the accompanying drawings, the numeral 10 designates the writing head of a book or flat-platen typewriting machine of the general type now commonly in use. This head is mounted for sliding reciprocatory movement on a pair of guide rails 11, whereby the head may traverse the flat platen and become positioned for operation of the type on the material positioned thereon. The usual construction of machines of this general character also includes a pair of transversely extending cross-bars 12 and 13, which connect the guide rails 11, and there is also included in the construction of the machine a sliding frame or

carriage 14, part only of which is illustrated, on which the writing head 10 is mounted. The line-spacing mechanism is operated by a shift bar 15 to which is connected a handle 16, and to said handle 16 pressure is applied by the operator for actuating the line-spacing mechanism, and thereby to move the writing head 10 over the platen.

The present invention contemplates a flat platen 17, which platen is connected to the cross-bars 12 and 13 and suitably fastened thereto to be held in rigid position thereon. At the edge portions of the platen 17 are located inwardly directed overhanging flanges 18, spaced a suitable distance above the face of the platen to provide guide channels, and into said guide channels the work or material to be printed upon or stenciled is introduced. As illustrating one instance 20 of such material, there is shown in Fig. 5 a record card 19, such as commonly used in merchandising establishments, said card having provision thereon for endorsement of transactions with the customer whose name is usually printed at the head of the card, as in the space 20. This card also includes a stencil sheet 21, of the usual fibrous material employed for this purpose, and said sheet has cut therein the name and address 30 of the customer so that the stencil sheet may be employed in the addressing of communications to the customer, and in other uses where the name and address of the customer is to be imprinted. This use of records of this nature is well known and need not be further dwelt upon.

It has been stated that the present invention aims to provide means whereby the name of the customer, and his address, if desired, may be accurately printed at the head 40 of the card 19, and likewise his name and address cut in the stencil sheet 21 at such point as to insure the same being located in the area covered by the normal ink spot thereof 45 when the card is placed in an imprinting machine or device. To this end provision must be made for properly positioning the card 19 on the platen 17. When introduced to the platen the edges of the card 19 are inserted 50 beneath the overhanging flanges 18, so as to occupy the guide channels formed between the same and the platen, and to facilitate this introduction the forward ends of the flanges 18, or the ends which are nearest 55 to the operator as the latter faces the machine, are cut away or flared, as at 22, thus permitting the card 19 to be easily passed into the space between the flanges 18. It is essential, however, that the initial positioning of the card on the platen shall be 60 accurately done, so that the printing space and the stencil sheet of the card may be properly located with respect to the writing head 10 when the latter is moved to the printing and cutting positions which it oc-

cupies in effecting these operations. For such purpose the platen 17 has adjacent to its rear end a pair of upwardly extending studs 23, and the top end of the card 19 contacts these studs, and thus is limited in its 70 movement when the card is introduced to the platen 17.

In order to prevent injury to the type of the writing head 10 in the stencil cutting operation, it is desirable that cushioning means 75 may be provided within the platen 17, and against which the impact of the type may be effected during the cutting operation. For this purpose the platen 17 has a transversely extending countersunk depression 24, which 80 lies in a plane below the upper surface of the platen. A rectangular frame 25 is arranged over this depression 24, the top surface of the frame 25 lying flush with the top surface of the platen 17, and through the frame 25 communication is established with the countersunk depression 24. The frame 25 has an outwardly flared mouthpiece 26, and through said mouthpiece 26 may be introduced a cushion sheet 27, which may be of 85 celluloid or other suitable material of yielding characteristics, thereby to provide a cushion for the impact of the type of the writing head 10. The location of the depression 24 and the frame 25 which overlaps the same 90 is such that when the card 19 is inserted between the flanges 18 and abuts the studs 23 the stencil sheet 21 will be positioned directly above the opening of the frame 25 and the cushion sheet 27. Therefore, as the type cut 95 the stencil sheet 21 liability of damage to the type is eliminated, the yielding character of the sheet 27 taking up the impact of the type and preventing such damage.

It has also been stated that the present invention aims to provide means for accurately positioning the writing head 10 in relation to the material to be printed upon or stenciled without the necessity of the operator 105 inspecting the area which receives the printing or which is cut, and without laboriously searching for the proper point thereon for effecting the desired operations. To such end there is mounted on one of the guide rails 11 a stop block 28 at one end of which 110 is located an upwardly extending contact head 29. The head 29 is in the path of movement of a connecting bar 30, which forms part of the machine frame or carriage 115 of the writing head when the writing head 10 is moved in a direction away from the operator as the operator faces the machine. The exact location of the stop block 28 is such that when the bar 30 contacts the head 29 the line of writing of the head 10 will 120 be in the space 20 of the card 19 as the latter occupies its position on the platen 17. Therefore, after the operator has placed the card 19 on the platen 17 in abutting relation 125 to the studs 23, the simple movement by the 130

operator of pushing the writing head 10 until such movement is stopped by engagement of the connecting bar 30 with the head 29, will position the writing head 10 in relation to the card so that the name of the customer may be written or typed upon the head of the card.

For effecting similar positioning of the head 10 with respect to the stencil sheet 21 to enable the latter to be cut by the type of the head a stop dog 31 is mounted upon the frame of the head 10, which dog is pivoted in a slotted block 32, as by a pin 33, or its equivalent. This dog 31 is in the form of a bell-crank lever, the longer arm having a link 34 connected thereto. The link 34 is also connected to a crank arm 35 carried by the rock shaft 15, and by these connections it is obvious that as the shaft 15 is rocked by the handle 16 to effect linear movement of the writing head 10, as when spacing, the stop dog 31 also will be rocked on its pivot 33, thereby elevating the shorter arm of the dog. The normal position, however, of the shorter arm of the dog 31 is such that when the carriage or frame on which the head 10 is mounted is moved toward the operator, the shorter arm of the dog 31 will contact the stop block 28, and thus bring the carriage to rest. In such position the line of writing, or the line of impact of the type of the head 10, will be within the stencil sheet 21, and in the area covered by the normal ink spot of the sheet when the card 19 is placed in the imprinting machine or device. This, therefore, insures the accurate cutting of the stencil sheet at such point that when the ink is applied to the sheet it will be applied to all the matter stenciled therein, so that a complete, uniform and entirely legible imprint of the stenciled matter will occur at the imprinting operation. At the time that the carriage thus is brought to rest by contact of the stop dog with the stop block 28, the head 10 is positioned for cutting the first line in the stencil sheet. For cutting the next succeeding line or lines, it is but necessary to depress the handle 16 of the line-shifting mechanism, and in the initial movement of such depression the nose of the dog 31 is elevated sufficiently high to clear the end of the stop block 28, and on the continued depression of the handle 16 so as to move the writing head 10 the distance of one line space, the nose of the dog 31 entirely clears the block 28. When thus positioned the second line may be cut in the stencil sheet, and if further lines are to be cut the writing head 10 is free to move to the new positions for such cutting by additional successive depressions of the handle 16 for the spacing movement of the head. If these additional lines be of sufficient number, the nose of the dog 31 ultimately will contact

with the head 29, and thus bring the carriage 10 to rest when such contact occurs, but at such time the line of impact of the type of the writing head 10 still will be within the stencil sheet 21 and in the area 70 covered by the normal ink spot. This insures that all the matter cut in the stencil sheet will be embraced by the application of the ink when the stencil is positioned in the imprinting machine or device. 75

From the foregoing description it is believed unnecessary further to set forth the operation of the mechanism, it being clearly apparent from such description. It is to be observed, however, that the flanges 18 serve 80 to retain the edges of the card 19 in close relation to the platen 17, so that the card lies flat upon the platen, and thus is so related to the impact of the type that but minimum effort is required to effect the printing and 85 cutting operations. The studs 23 insure the initial positioning of the card with accuracy upon the platen 17, and the stop block 28 in its co-acting relation with the cross-bar 30 and the stop dog 31 enable the writing head 10 to be positioned accurately relatively to the space of the card on which the printing is to be effected, as well as with 90 respect to the stencil sheet which also is to be cut, so that the writing mechanism becomes positioned in definite and predetermined location over the platen, which will permit the type to fall in the desired area 95 on the surface to be printed upon or cut. 100

I claim:

1. In an attachment of the class described, the combination with the writing head of a flat-platen typewriting machine of a platen arranged in a plane below said writing head, guide flanges associated with said platen 105 for guiding the surface to be acted on by the writing head to initial position in its introduction to the platen, the latter being provided with a countersunk depression extending transversely and adapted to slidably 110 receive a cushioning element, a cushioning element located in said countersunk depression for cushioning the impact of the type of the writing head, and means with which said head co-operates to arrest its movement over said platen and position the head 115 so that its line of writing will occupy a predetermined position with respect to the surface to be written upon. 120

2. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head 125 in printing position with respect to the work 130

supported by the platen, and means associated with the writing head to engage such stop in reverse direction of movement of the head to limit movement of the head in such reverse direction and locate the head in stencilling position with respect to the work.

3. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head in printing position with respect to the work supported by the platen, and means associated with the writing head to engage said stop in the reverse direction of movement of the head to limit movement of the head in such reverse direction and locate the head in an initial stencilling position with respect to the work, the last mentioned means including provision for varying its engaging relation to said stop, whereby to permit variation of the stencilling position of the head with respect to the work.

4. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head in printing position with respect to the work supported by the platen, and means associated with the writing head to engage said stop in reverse direction of movement of the head to limit movement of the head in such reverse direction and locate the head in stencilling position with respect to the work, the operative relation of the last mentioned means to said stop being controlled by the line-spacing mechanism of the writing head.

5. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head in printing position with respect to the work supported by the platen, and means associated with the writing head to engage said stop in the reverse direction of movement of the head to limit movement of the head in such reverse direction and locate the head in stencilling position with respect to the work.

the head in an initial stencilling position with respect to the work, the last mentioned means including provision for varying its engaging relation to said stop, whereby to permit variation of the stencilling position of the head with respect to the work, the operative relation of the last mentioned means to said stop being controlled by the line-spacing mechanism of the writing head.

6. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head in printing position with respect to the work supported by the platen, and a pivoted dog associated with the writing head to engage said stop in the reverse direction of movement of the head to limit movement of the head in such reverse direction and locate the head in stencilling position with respect to the work.

7. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head in printing position with respect to the work supported by the platen, a pivoted dog associated with the writing head to engage said stop in the reverse direction of movement of the head to limit movement of the head in such reverse direction and locate the head in an initial stencilling position with respect to the work, and means for varying the engaging relation of the dog to said stop, whereby to permit variations of the stencilling position of the head with respect to the work.

8. In an attachment of the class described, the combination with the writing head of a flat-platen typewriting machine, and the support on which said head is slidably mounted, of a platen associated with said support, a stop carried by said support to be contacted by the writing head in one direction of movement of the latter with respect to said support, whereby to limit movement of said head in such direction and locate the head in printing position with respect to the work supported by the platen, and a pivoted dog associated with the writing head to engage said stop in the reverse direction of movement of the head to limit movement of the head in such reverse direction and locate the head in stencilling position with respect to the work.

tion and locate the head in stencilling position with respect to the work, the operative relation of said dog to said stop being controlled by the line-spacing mechanism of 5 the writing head.

9. In an attachment of the class described, the combination with the writing head of a flat-platen typewriting machine, and the support on which said head is slidably 10 mounted, of a platen associated with said support, a stop carried by said support to be contacted by the writing head in one direction of movement of the latter with respect to said support, whereby to limit 15 movement of said head in such direction and locate the head in printing position with respect to the work supported by the platen, a pivoted dog associated with the writing head to engage said stop in the reverse direction of movement of the head to limit movement of the head in such reverse direction and locate the head in an initial 20 stencilling position with respect to the work, and means for varying the engaging relation 25 of the dog to said stop, whereby to permit variations of the stencilling position of the head with respect to the work, the operative relation of said dog to said stop being controlled by the line-spacing mechanism of 30 the writing head.

10. In an attachment of the class described, the combination with the writing head of a flat-platen typewriting machine, and the support on which said head is slidably 35 mounted, of a platen associated with said support, a stop block carried by said support and provided with an upwardly extending contact head, said stop block being contacted by the writing head in one direction of movement of the latter with respect to said support whereby to limit movement of the head in such direction and locate the head in printing position with respect to the work supported by the platen, 40 a pivoted dog associated with the writing head to engage the end of said stop block in the reverse direction of movement of the head to limit movement of the head in such reverse direction and locate the head in an initial 45 stencilling position with respect to the work, and means for varying the position of engagement of the dog to said stop block, whereby to clear the dog from engagement with the end of said stop block 50 and position the dog for engagement with the contact head of the stop block to limit the stencilling position of the writing head with respect to the work.

11. In an attachment of the class described, the combination with a writing head of a flat platen typewriting machine, of a platen arranged in a plane beneath the said

writing head, a stop on said platen, said stop comprising two blocks one of which directly engages the writing head, a dog carried by 65 said writing head and operatively associated with a line spacing mechanism of said head for engagement with one of said stop blocks to arrest the movement of said writing head, 70 said dog being releasable from said stop block by the operation of said line spacing mechanism and being subsequently engageable with the second stop block upon continued operation of said line spacing mechanism. 75

12. The combination of a flat platen having longitudinal guides, a writing machine continuously movable on said guides along said platen, either in forward or backward direction, said machine having a line spacing mechanism for moving it backwards step by step, stop means for stopping the machine on a predetermined point in the forward movement to bring it to a first writing position over a predetermined portion of 80 the length of the platen, a second stop means for stopping continuous backward movement thereof in backward direction from said first position at a predetermined second writing position along said platen, 85 means associated with said line spacing mechanism for causing further backward movement of said machine past said second writing position upon actuation of said line spacing mechanism, and a third stop means 90 for arresting any further backward movement of said machine. 95

13. The combination of a flat platen having longitudinal guides, a writing machine continuously movable on said guides along 100 said platen, either in forward or backward direction, said machine having a line spacing mechanism for moving it backwards step by step, stop means for stopping the machine on a predetermined point in the forward movement to bring it to a first writing position over a predetermined portion of the length of the platen, a second stop means for stopping continuous backward movement thereof in backward direction from 105 said first position at a predetermined second writing position along said platen, means associated with said line spacing mechanism for causing further backward movement of said machine past said second writing position upon actuation of said line spacing mechanism, and a third stop means 110 for arresting any further backward movement of said machine, said platen carrying a stopping member common to the first, second and third stopping means. 115

In testimony whereof I have hereunto signed my name.

NATHAN C. HEATON.

CERTIFICATE OF CORRECTION.

Patent No. 1,660,008.

Granted February 21, 1928, to

NATHAN C. HEATON.

It is hereby certified that error appears in the printed specification of the above numbered patent requiring correction as follows: Page 1, line 35, for the word "effect" read "effort"; and that the said Letters Patent should be read with this correction therein that the same may conform to the record of the case in the Patent Office.

Signed and sealed this 20th day of March, A. D. 1928.

Seal.

M. J. Moore,
Acting Commissioner of Patents.
